UNITED STATES PATENT OFFICE.

CHARLES P. PRICE, OF BOSTON, MASSACHUSETTS.

GAS HEATER.

Application filed January 15, 1926. Serial No. 81,501.

This invention relates to improvements in gas heaters and more particularly to damper or control devices for such heaters.

One of the objects of this invention is to provide a gas heater which is portable and may be placed in any part of a room or apartment to heat the same, and which is assembled with a limited combustion chamber and a mixing chamber thereabove, with a communication between the two which may be closed or regulated at will by means of an appropriate damper.

Another object of this invention is to provide a damper construction by which the flow of air between the combustion chamber and the mixing chamber may be exactly regulated according to the desires of the operator and the requirements of the occasion.

Two forms of execution of the structure are shown on the accompanying drawings by way of example, and

Figure 1 is a vertical section through a gas heater according to this invention.

Fig. 2 is a plan view of the heating plate.

Fig. 3 is a section on line 3—3 of Fig. 1,

Fig. 4 is a fragmentary section similar to Fig. 1 but showing a modified form of the invention.

According to this invention, the gas heater is mounted upon legs 10—10 and comprises the casing 11 which is closed by a top 12 at its upper end and has the bottom plate 13 therein with apertures 14 for the admission of air for combustion and for heating. The

pipe 15 leads from any suitable source of combustible gas to a shut-off and regulating valve 16, and thence by the riser pipe 17 to the burner pipe 18 which extends in the usual manner for the length of the stove and has a number of apertures 19 in its upper surface through which the gas may escape and be ignited. It will be understood that this arrangement is merely by way of example and illustrates a means of producing a gas flame within the combustion chamber.

The lower part of the gas stove is shut off from the upper part by a double partition and thereby constitutes a combustion chamber, since in it the combustion of the gas occurs, while the upper compartment may be referred to as a mixing chamber since in it the thorough mixing of the air occurs before this air is discharged into the room. This double partition is composed of a thin sheet metal bottom plate 20 having long slots 21 therein and supported by the

brackets 22 upon the casing 11. The second wall of the double partition is formed by a relatively heavy, e. g., cast-iron plate 23, having a number of apertures 24 therein. This plate is supported from the casing 11 by the brackets 25.

The low intermediate chamber I constituted between these double partition walls contains a damper plate 26 which rests loosely upon the lower plate 20 and is guided by the front and rear walls of the casing 11. It is made shorter than the plate 20 by an amount at least equal to the width of the slots 21 in the plate 20. A handle 27 is secured to the plate 26 and extends through one end of the stove to the exterior so that by its aid the plate may be moved back and forth as an operator may desire. The plate 26 has a number of slots 28 therein which in size correspond to the corresponding slots 21 of the plate 20; and when the sliding plate 26 is in one end position it acts as a damper to shut off flow of air from the lower compartment C to the intermediate compartment I and thence to the mixing chamber M; and when in the opposite end position, it affords a free flow between these chambers through the aligned slots 21 and 28.

The stove is provided as customary with a front door 30 in its lower portion and the apertured door 31 in its upper portion and openings 32 may be provided which communicate between the mixing chamber M and the atmosphere.

In the modified form shown in Fig. 4, the plate 20^a is of thin sheet metal as before and has a number of openings 21^a therein. The upper plate 23^a is of thin material such as cast-iron, and in this case has a number of slots 24^a therein. The sliding plate 26^a is substantially identical with that described with regard to the first modification, but in this case is supported upon the upper plate 23^a, and has slots 28^a to register with the slots 24^a thereof. The two plates 20^a and 23^a are supported from the casing 11 by the channel iron brackets 22^a. The method of operation of these devices is as follows: The gas being ignited and forming a flame of either illuminous or Bunsen type through the openings 19 burns in the air contained in the chamber C. This heated air rises and flows through the slots 21—28 to an extent determined by their overlap and the cross section of passage thus afforded. It

will be understood that fresh air flows in at the bottom of chamber C through the openings 14 to replace this air, and that the mass of air in the chamber C is entrained and caused to move upward into the intermediate chamber I, and thence through the openings 24 into the mixing chamber M, where the air currents mingle and the air escaping through the slots at 31 and 32 is of a substantially uniform temperature. In this way, local overheating is avoided and the heat is found to spread out better within the room and not to merely collect near the ceiling. Furthermore, the thick plate 23 serves as a heat regulator to stabilize and maintain constant the temperature of the air in spite of momentary variations of the intensity of the burner or local currents occurring within the combustion chamber C. The heater may be regulated by means of the valve designated at 16 for the gas and by moving the damper handle 27 to vary the cross section of passage between the several chambers.

It is obvious that the invention is not limited to the specific forms of execution shown, but that the form, arrangement and dimensions may be varied within the scope of the appended claims.

I claim:—

1. In a gas heater, a casing divided by a double-walled horizontal partition into a lower combustion chamber and an upper mixing chamber, one of said walls being of substantial mass to maintain constant the temperature of the air flowing into said upper mixing chamber, said partition having openings therethrough, and a damper to

regulate the effective area of said openings.

2. In a gas heater, a casing having a perforated bottom, an intermediate double partition to divide the same into a lower combustion chamber and an upper mixing chamber, a gas burner in said combustion chamber, said partition having a member of substantial mass to maintain constant the temperature of the flowing air, and having apertures therein for the passage of air from said combustion chamber to said mixing chamber, and a damper to regulate the effective area of said openings.

3. In a gas heater, a casing, a perforated bottom plate in said casing, a thin perforated intermediate plate in said casing to define with the perforated bottom plate a combustion chamber, a gas burner in said combustion chamber, a sliding plate having apertures therethrough adapted to be brought into and out of register with the openings of said intermediate plate to regulate the effective area of passage therethrough, and a thick intermediate plate having apertures therethrough disposed above said sliding plate.

4. In a gas heater, a casing, and a pair of horizontal partitions to divide said casing into an upper mixing chamber and a lower combustion chamber, and to provide between themselves a low intermediate chamber, one of said partitions being of substantial mass to maintain constant the temperature of the air flowing through said low intermediate chamber.

In testimony whereof, I affix my signature.

CHARLES P. PRICE.
